UNITED STATES PATENT OFFICE

142,218

DESIGN FOR A FLUID FUEL BURNING STEAM AND HOT WATER GENERATING UNIT

William Lelgemann, Grill, Pa.

Application January 31, 1945, Serial No. 117,695

Term of patent 14 years

(Cl. D81—2)

To all whom it may concern:

Be it known that I, William Lelgemann, a citizen of the United States of America, residing at Grill, in the county of Berks and State of Pennsylvania, have invented a new, original, and ornamental Design for a Fluid Fuel Burning Steam and Hot Water Generating Unit, of which the following is a specification, reference being had to the accompanying drawings forming part thereof.

Figure 1 is a top plan view of a fluid fuel burning steam and hot water generating unit embodying my new design.

Fig. 2 is a side elevational view of the unit shown in Fig. 1, as seen by looking at the latter in the direction indicated by the arrow 2.

Fig. 3 is a side elevational view of the unit shown in Fig. 1, as seen by looking at the latter from the side opposite to that disclosed in Fig. 2.

Figs. 4 and 5 are, respectively, front and rear elevational views of the unit shown in Fig. 1.

I claim:

The ornamental design for a fluid fuel burning steam and hot water generating unit, as shown.

WILLIAM LELGEMANN.
